PEN ATTACHMENT

Andrew W. Huntress, Washington, D. C.

Application December 17, 1937, Serial No. 180,436

4 Claims. (Cl. 120—114)

The present invention relates generally to pens, and more particularly to an attachment therefor, which together with the pen provides a reservoir in which a considerable amount of ink is stored by dipping the pen into a supply thereof, the ink being gradually fed to the pen point so that the latter can be used for an appreciable longer period of time, than the ordinary pen without replenishing the same with ink.

The primary object of the invention resides in providing a pen attachment of the above mentioned character designed to be quickly and conveniently associated with any conventional style of pen, and capable of being easily removed therefrom for use with another pen as the occasion may require.

The invention is in the nature of a feeder attachment for the pen, and is supported upon the latter in spaced relation thereto, thus providing a reservoir in which an additional quantity of ink is stored for the purpose above mentioned.

In carrying out the invention, the attachment is stamped from a single blank of material to 25 more or less conform to the cross sectional contour of the pen, and characterized with a tongue utilized to support the attachment definitely spaced from the pen, and also to feed the ink from the reservoir to the latter.

More specifically stated, the invention comprehends an attachment for the above mentioned purposes, having a tongue projecting obliquely from the under side thereof and adapted to be received by the usual opening or slot formed 35 in the pen, the tongue engaging the wall of said opening or slot to prevent relative movement of the pen or attachment toward each other, while the tongue is further utilized to convey ink from the reservoir to the pen point.

The nature and advantages of the invention will be better understood when the following detail description is read in connection with the accompanying drawing, the invention residing in the construction, combination and arrangement 45 of parts as claimed.

In the drawing forming part of this application like numerals of reference indicate similar parts in the several views and wherein:

Figure 1 is a side elevation.
50 Figure 2 is a longitudinal sectional view through the pen and attachment.
Figure 3 is a front end elevation.
Figure 4 is a top plan view.
Figure 5 is a view of the blank.
55 Figure 6 is a view of a modified construction.

Figure 7 is a view of one conventional type of pen.

Figure 8 is a view of another conventional type of pen.

Referring to the drawing 10 indicates a portion of a pen holder of any construction, the pen being indicated at 11. The latter may be of any conventional type and provided with the usual slot or opening 12, as illustrated in Figures 7 and 8.

The attachment forming the subject matter of the present invention consists of a single element which may be constructed from any suitable material, preferably metal. The attachment is indicated at 13 and as illustrated is 15 adapted to be supported on the pen 11 substantially in spaced parallelism therewith. The attachment terminates an appreciable distance from the point of the pen so as not to interfere with the use of the latter. Obviously, the space 20 between the pen and the attachment therefor defines an ink reservoir in which a considerable amount of ink is taken up and stored incident to dipping the pen in a supply of ink. Consequently, the capacity of the pen is materially increased and it can be used for a much longer period of time than the ordinary pen, without replenishing the same with ink, in addition to saving much time and effort expended in frequent dipping of the ordinary pen.

The attachment may be removably secured to the pen in any suitable manner, but I preferably provide a pair of bendable lugs 14 adjacent one end thereof adapted to be bent about the edges of the shank of the pen. This end of the element 35 is also formed with an offset extension 15 which is adapted to repose on the shank of the pen as shown.

However, with a view of holding the attachment rigidly spaced a predetermined distance 40 from the pen I provide the attachment with an obliquely disposed tongue 16 which projects downwardly and forwardly from the under side of the attachment adjacent the innermost end thereof. If desired, the tongue may be of a 45 resilient nature or possess the inherent resiliency of the material from which the attachment is made. The tongue 16 is preferably stamped from the attachment and has its free end received by the opening or slot 12 of the pen as illustrated. 50 The free end of the tongue engages the walls of the opening or slot 12 and by virtue of its angularity to the pen, the latter and said attachment are rigidly held against movement toward each other, thereby providing a reservoir to hold 55

a maximum amount of ink for a long continued use of the pen without the necessity of replenishing it by dipping and provide for a more uniform and gradual flow of ink from the reservoir to the pen. The free end of the tongue 16 may be slightly tapered to effectively engage the walls of the opening or slot 12 of the pen for the purpose intended, or it may be reduced as shown to provide shoulders 17 for this purpose. In either event, the attachment can be easily and conveniently associated with the pen or removed therefrom for use with another pen as the occasion might require. In order to associate the attachment with the pen, it is only necessary to place the tongue 16 against the walls of the opening or slot 12 thereof, and then bend the lugs 14 about the adjacent edges of the pen, the extension 15 resting on the pen shank. The attachment is extremely simple in construction and can be manufactured and sold at a very nominal cost, either as an article of manufacture or as part of the pen as a complete product.

While it is believed that from the foregoing description the nature and advantages of the invention will be readily understood, I desire to have it known that I do not limit myself to what is herein shown or described, and that such changes may be resorted to as fall within the scope of what is claimed.

30   What is claimed is:

1. The combination with a pen having an opening therein, of an attachment comprising an element designed to conform to the cross sectional contour of the pen and adapted to be supported above the pen in spaced parallelism therewith to define an ink reservoir of uniform dimensions throughout its length, and means for securing the attachment in place including a combined supporting tongue and feeder carried by said

element and positioned in said opening of the pen.

2. As a new article of manufacture, an attachment for pens comprising an element designed to conform to the cross sectional contour of the pen, and means carried thereby for removably securing the element to the pen in uniformly spaced parallelism therewith substantially throughout its length, said means including an obliquely disposed tongue positioned in the opening of the pen and in engagement with the edge thereof and utilized to assist in supporting said element and as a feeder for said pen.

3. As a new article of manufacture, an attachment for pens comprising an element designed to conform to the cross sectional contour of the pen and adapted to be supported thereby in spaced parallelism therewith to provide an ink reservoir, means at one end of the element for securing the same to the shank of the pen, and a tongue projecting angularly from the under side of the element and positioned within the opening of the pen and in engagement with the edge thereof to assist in supporting the element parallel thereon and as a feeder for said pen.

4. The combination with a pen having an opening therein, of an attachment comprising an element designed to conform to the cross sectional contour of the pen, and means carried thereby for securing the attachment in place, said means including a feeder tongue projecting downwardly and forwardly from the under side of the attachment and having a reduced extremity received by said opening and engaging the edge thereof to support the attachment equidistantly spaced from the pen throughout the major portion of its length.

ANDREW W. HUNTRESS.
